CLAIM

(***) Term: **14 Years**

The ornamental design for a chassis with mirror, for an under vehicle inspection device, as shown and described.

DESCRIPTION

(21) Appl. No.: **29/204,369**

(22) Filed: **Apr. 27, 2004**

(30) **Foreign Application Priority Data**

Oct. 31, 2002 (GB) 3014989

FIG. 1 is a top plan view of a chassis with mirror, for an under vehicle inspection device showing an exemplary example of my new design;

(51) **LOC (8) Cl.** **12-02**

FIG. 2 is an underneath plan view of the chassis with mirror of FIG. 1;

(52) **U.S. Cl.** **D34/23**

FIG. 3 is a view of one side of the chassis with mirror of FIG. 1;

(58) **Field of Classification Search** D34/23,

FIG. 4 is a view of another side of the chassis with mirror of FIG. 1;

D34/12; 280/32.5, 32.6, 79.11, 79.2, 79.7

FIG. 5 is a top perspective view of the chassis with mirror of FIG. 1;

See application file for complete search history.

FIG. 6 is a further top perspective view of the chassis with mirror of FIG. 1;

(56) **References Cited**

FIG. 7 is an underneath perspective view of the chassis with mirror of FIG. 1; and,

1,853,007 A * 4/1932 Stannard 280/32.6

FIG. 8 is a further underneath perspective view of the chassis with mirror of FIG. 1.

D351,707 S * 10/1994 Pill D34/23
